UNITED STATES PATENT OFFICE.

ALFRED L. EUSTICE, OF CHICAGO, ILLINOIS.

PLUG-FUSE.

1,344,296.

Specification of Letters Patent. Patented June 22, 1920.

Application filed August 23, 1918. Serial No. 251,091.

To all whom it may concern:

Be it known that I, ALFRED L. EUSTICE, a citizen of the United States, residing at Chicago, in the county of Cook and State 5 of Illinois, have invented certain new and useful Improvements in Plug-Fuses, of which the following is a specification.

This invention relates to plug fuses.

One of the objects is to simplify and improve the general construction of plug fuses.

Another object is to construct a plug fuse in a novel manner whereby it can be observed readily whether or not the fusible element has become ineffective.

15 Another object is to provide a novel plug fuse adapted to meet the various requirements for successful commercial usage.

These and other objects are accomplished by means of the plug fuse disclosed on the 20 accompanying sheet of drawings, in which—

Figure 1 is a side elevation of my plug fuse;

Fig. 2 is an end elevation of one end of the plug fuse;

25 Fig. 3 is an end elevation of the opposite end of the plug fuse; and

Figs. 4 and 5 are longitudinal sectional views of the same plug fuse on an enlarged scale taken at right angles with respect to 30 each other.

The various novel features of my invention will be apparent from the following description and drawings and will be particularly pointed out in the appended claims.

35 Referring to the figures of the drawings, it will be noted that I have provided a plug fuse including a hollow base 10 of insulating material provided with a gnarled head 11 whereby the plug fuse may be readily screwed into a socket. The barrel portion 40 of this base 10 is provided with an external threaded portion 12 and with a longitudinally extending groove 13 which interrupts the threads. A disk 14 of insulating material closes one end of the hollow base 10 and is provided with two apertures 15 through which one end portion of a fusible element 16 is threaded for forming one terminal, it being understood that this end

45 of the fusible element is doubled back upon itself on the inside of the disk 14 for securing the former to the latter. The intermediate portion of the fusible element 16 extends through the hollow barrel portion 50 of the plug 10 and near the head of this base is provided with a drop-out link 17 formed

by two narrow neck portions 18. Beyond this drop-out link portion, the fusible element extends toward the disk 14 and passes to the outside of the fuse base and occupies 60 the groove 13. A threaded shell 17' of conducting material is threaded over the threaded barrel portion of the base 10 and has a flange 18 which holds the disk 14 intermediate said flange 18 and one end of 65 the base 10. To make a good electrical contact between the shell terminal 17' and its co-operating end of the fusible member, a drop of solder may be used. The intermediate looped portion of the fusible element 70 16 is supported by an insulating member 19, preferably of mica, which normally is supported in oppositely arranged grooves 20 formed on the inside of the barrel portion of the base 10. This insulating member 75 19 also rests in a groove 21 on the inside of the disk 14 for preventing the passage of a destructive arc between oppositely arranged portions of the fusible element.

In order that the condition of the fusible 80 element may be readily observed, I have provided the head end of the plug with a window 22, which preferably is of mica, or any other suitable transparent material, said window being held between oppositely arranged flanges 23 formed integrally with a metal window frame 24, the outer end of which, after being inserted into the opening 25 of the base, is spun over at 26 to form a flange to prevent displacement of the 85 frame, co-operating in this respect with one of the flanges 23. It will be appreciated that the flanges 23 may be formed while assembling the window frame in the base or may be formed previously thereto. If the 90 fusible element is rendered ineffective for any reason, the same will be readily observed through the window 22, whereupon the fuse may be repaired.

By means of this arrangement a plug fuse 100 simple in construction and adapted for commercial usage is provided.

It is my intention to cover all modifications falling within the spirit and scope of the following claims.

I claim:

1. A plug fuse including, in combination, a hollow base having an external groove therein and having oppositely arranged grooves on the inside thereof, an apertured 110 disk closing one end of the base, a fusible member having one portion extending

- through the apertured disk to form one terminal and having another portion extending along said groove, a conducting terminal shell fitting over said base for securing the disk thereto and being electrically connected to the fusible element, and a supporting member for an intermediate portion of the fusible member retained by the grooves on the inside of said base.
5. A plug fuse including, in combination, a hollow base, a fusible member mounted therein, a flanged window frame mounted wholly within one end of the base, and a transparent member mounted in said frame between its flanges whereby the transparent member is securely held and whereby the condition of the fusible element may be observed.
10. 2. A plug fuse including, in combination, a hollow base, a fusible member mounted therein, a flanged window frame mounted wholly within one end of the base, and a transparent member mounted in said frame between its flanges whereby the transparent member is securely held and whereby the condition of the fusible element may be observed.
15. 3. A plug fuse including, in combination, a hollow base, a fusible member mounted therein, a flanged window frame mounted in one end of the base, and a transparent member mounted in said frame between its flanges whereby the transparent member is securely held and whereby the condition of the fusible element may be observed, a portion of said frame being spun over for securing the frame within said base.
20. 4. A plug fuse including, in combination, a hollow base having an external groove therein, an apertured disk closing one end of the fuse, a fusible element having one portion extending through the apertured disk to form one terminal and having another portion extending along said groove, said fusible element including a drop-out portion, a conducting terminal shell fitting over said base for securing the disk thereto and being electrically connected to the fusible member, and a transparent member closing the other end of the base and being arranged adjacent a drop-out portion of the fusible element whereby the condition of the fusible element may be observed.

Signed at Chicago, Illinois, this 17th day 45 of August, 1918.

ALFRED L. EUSTICE.
